UNITED STATES PATENT OFFICE

CHARLES E. VAN NORMAN, OF SPRINGFIELD, MASSACHUSETTS, ASSIGNOR TO VAN NORMAN MACHINE TOOL COMPANY, OF SPRINGFIELD, MASSACHUSETTS, A CORPORATION OF MASSACHUSETTS

SLIDE MECHANISM FOR PRECISION GRINDING MACHINES

Original application filed April 29, 1926, Serial No. 105,458. Divided and this application filed April 9, 1928.
Serial No. 268,712.

This invention relates to improvements in precision grinding machines, and has particular reference to the construction of the sliding head thereof, whether it be the tool or the work head. It has for its object the provision of a slide mounting and of a slide operating mechanism by means of which a high degree of accuracy may be attained in an initial manual positioning of the slide and a fine adjustment superimposed upon this coarse initial adjustment with an improved rigidity and accuracy of the parts. The present application is a division of my prior application Serial No. 105,458, filed April 29, 1926.

Referring to the drawing:

Fig. 1 is a partial end elevation of a grinding machine embodying my invention;

Fig. 2 is a detail plan of a portion of certain lever mechanism shown in Fig. 1;

Fig. 3 is an elevation corresponding to Fig. 1 but on a slightly larger scale and with the parts in a slightly different position of operation;

Fig. 4 is a section on line 4—4 of Fig. 1; and

Fig. 5 is a section on line 5—5 of Fig. 1.

Since a description of the entire grinding machine to which my invention has been applied is not necessary to the understanding of the invention itself, I have shown the base 10 of the machine and the tool slide 11 in partial outline only, and have omitted any illustration of the work head. A complete description of the general type of machine may be found in my Reissue Patent No. 13,892, dated March 16, 1925, and in my pending application Serial No. 105,458, filed April 29, 1926. The mounting of the tool slide and the manner in which the initial positioning adjustment is given to it are different in the present case than in the machines referred to, and form the subject-matter of the present invention.

In precision grinding it is of the utmost importance to have the parts as rigid as possible, as vibrations will be reflected in irregularities in the surface of the finished article.

The base 10 is made heavy, and the slide 11, besides having a bearing surface over its

bottom, is provided with a V-slide 12 coacting with a similarly shaped groove in the base to provide a self-adjusting bearing of as large an area as possible. Also mounted directly upon the base 10 is a slide 13 slideable in suitable ways 14. Upon this latter slide is fixed a nut 15 receiving a screw 16 fixed longitudinally with respect to the slide 11 and rotatable by a hand-wheel 17 or other suitable mechanism. In practice, this mechanism is an automatic device operable to rotate the screw 16 periodically and thus cause a slow movement of slide 11 relative to slide 13. Such a mechanism is described in my patent and application above referred to.

While the longitudinal movement of the tool slide 11 is determined by its screw and nut engagement with slide 13, its bearing is directly upon the heavy base rather than upon the other slide. In prior art devices, these slides have been directly superimposed, one having bearing upon the other. The tandem arrangement of the bearing surfaces has allowed the defects in both to become additive, and has introduced errors into the work which the present construction avoids. Not only is this additive effect removed, but the construction here described presents the further advantage that the transmission of vibrations to the tool slide is greatly reduced. Each slide is mounted directly upon the heavy base, and any shocks developed in them are absorbed by the base and not transmitted through to the tool.

A further feature of my invention is the mechanism for positioning and locking the slide 13. This slide is used to remove the tool head from the work head when it is desired to insert a fresh piece to be ground. Before starting the grinding on the new work piece, the slide 13 is returned to its normal position and locked there, further movement of the tool head being secured by moving slide 11 by means of the slow feed. In precision grinding it is of great importance to locate slide 13 in its normal position with great accuracy.

Secured to the bottom of slide 13 is a rack 18, engaged by a pinion 19 secured upon a shaft 20 having bearings in the base 10. A

lever 21 fastened to the outer end of the shaft affords a handle by means of which the operator may move the slide rapidly into or out of its work-engaging position. Secured to the end of slide 13 is a bracket 22 into which is threaded a stop screw 23 held in place by a lock nut 24 and striking against an abutment 25 on the base 10. In cases where the rapid slide movement shifts one slide with respect to the other rather than, as in the case shown, both slides with respect to the base, this abutment would be on the second slide rather than on the base. The features of the invention relating to the lever mechanism are, of course, applicable to any slide construction.

As the slide is moved into its work-engaging location with stop 23 against abutment 25, its position, from the standpoint of precision grinding, varied considerably in prior art devices according to the manner in which the operator handled the lever 21. If he exerted considerable force on the lever, the screw and abutment were slightly distorted; whereas, if he used only sufficient force to bring the slide into place, this distortion would not occur. Thin films of lubricating oil between moving parts also would be pressed out under a heavy force but would be unaffected where the pressure was light. These variations are, of course, not apparent to the eye but they appear in the finished work as a change in size.

A further chance for variation in position of the slide is found in the speed at which the stop screw strikes the abutment. If the speed was great enough so that there was a distinct blow, there would be a rebound due to the elasticity of the parts which would again vary the relative positions of the tool and the work. The amount of this rebound would of course vary with the speed at which the operator moved the lever, and this, as well as the force with which the operator pressed the lever in place, would vary with different operators and even at different times with the same operator.

I have provided means by which these inaccuracies are avoided. To reduce the pressure variations, I provide an abutment 26 (Fig. 3) on the lever 21 positioned to strike against an adjustable screw stop 27 secured to a lug 28 projecting from the base 10 and held in place by a lock nut 29. This lock nut may also hold a hand grip 30. The adjustable stop 27 is set so that abutment 26 strikes it at exactly the same instant that screw 23 strikes abutment 25. It is thus made impossible for sufficient pressure to be applied to the slide to cause distortion.

To lock the lever 21 in position, a latch handle 31 is pivoted at 32 to the lever, being pressed away by a spring 33. A latch plate 34 is secured to the handle 31 and is adapted to snap under a stationary latch plate 35

mounted on the base 10. To prevent overtravel of the handle due to spring 33, a stop 36 may be provided, extending from the handle adjacent the side of the lever.

In order to eliminate the variations in slide position due to the speed with which the lever is moved, I have provided means for checking this speed when the lever nears the end of its motion. In the case shown, this means consists in a leaf spring 37 attached to the lever and striking against the lug 28. This spring absorbs all the inertia of the parts and forces the operator to press the lever home so that no substantial impact can result.

I claim:

1. In a machine of the class described having work and tool supporting members, a bed, a slide movable on the bed and upon which one of said supporting members is carried, means for actuating said slide, a member for operating said actuating means, a slide stop on said slide for abutting said bed to limit the movement of said slide, a stop for limiting the movement of said operating member which is adjustable so as to abut against the operating member simultaneously with the abutting of the slide stop with the bed, and resilient means associated with said operating member arranged to cushion the movement thereof as it approaches the stop therefor.

2. In a machine of the class described having work and tool supporting members, a bed, a slide movable on the bed and upon which one of said supporting members is carried, means for actuating said slide including a lever for operating said actuating means, a slide stop on said slide for abutting said bed to limit the movement of said slide, a stop for limiting the movement of said lever which is adjustable so as to abut the lever simultaneously with the abutting of the slide stop and bed, resilient means associated with said lever arranged to restrain or cushion the movement thereof as it approaches the lever stop, and locking means for locking said lever against said lever stop.

3. In a machine of the class described having work and tool supporting members, a slide upon which one of said supporting members is carried, means for actuating said slide including a rotatable shaft, an operating lever carried by said shaft, a lever stop to limit the movement of said lever, and resilient means carried by said lever arranged to cushion or restrain the movement of said lever just prior to its abutment with the stop.

4. In a machine of the class described having work and tool supporting members, a slide upon which one of said supporting members is carried, means for actuating said slide including a rotatable shaft, a slide stop to limit the movement thereof, an operating lever on said shaft, a lever stop adjustable to arrest movement of said lever at the same

instant that the slide stop arrests the movement of the slide, a resilient lever restraining means to retard the movement of said lever as it approaches said lever stop, and a grip extending below said lever for engaging simultaneously with said lever to facilitate the movement of said lever against the action of said restraining means to position against said lever stop.

10 5. In a machine of the class described having work and tool supporting members, a slide upon which one of said supporting members is carried, means for actuating said slide including a rotatable shaft, a slide stop to limit the movement of said slide, an operating lever on said shaft, a lever stop adjustable to arrest the movement of said lever at the same instant that the slide stop arrests the movement of the slide, a resilient lever restraining means to retard the movement of said lever as it approaches said lever stop, a grip extending below said lever for engaging simultaneously with said lever to facilitate the movement of said lever against the action of said restraining means into position against said lever stop, and a releasable lock for locking said lever against said stop.

6. In a machine of the class described having a work support, a bed, a pair of slides each having direct bearing upon the bed, a tool head carried upon one of the slides, means for causing slow relative movement between the two slides for advancing the tool head carrying slide toward the work, and quick motion mechanism for shifting both slides towards or away from the work.

7. In a machine of the class described having a work support, a bed, a pair of slides each having direct bearing upon the bed, a tool head carried upon one of the slides, means for causing slow relative motion between the two slides for advancing the tool head towards the work, means including an operating lever for advancing the second slide toward the work, a stop limiting the motion of the second slide, and a second stop engaging the operating lever for restraining its movement simultaneously with the motion of the slide.

8. A grinding machine of the type having work and tool supporting heads in which one of the heads is carried by a pair of superposed slides adjustable both with respect to the machine bed and with respect to each other, wherein each slide is provided with separate bearings supported directly by the bed.

In testimony whereof I have affixed my signature.

60 CHARLES E. VAN NORMAN.
